UNITED STATES PATENT OFFICE.

EDWARD THOMAS, OF NEW YORK, N. Y., ASSIGNOR TO UNDERWOOD COMPUTING MACHINE COMPANY, OF NEW YORK, N. Y., A CORPORATION OF NEW YORK.

COMPUTING MACHINE.

1,413,999.

Specification of Letters Patent. Patented Apr. 25, 1922.

Application filed December 1, 1919. Serial No. 341,749.

To all whom it may concern:

Be it known that I, EDWARD THOMAS, a citizen of the United States, residing in New York city, in the county of New York and State of New York, have invented certain new and useful Improvements in Computing Machines, of which the following is a specification.

This invention relates to computing machines, and is herein described as applied to an Underwood standard bookkeeping machine, many of the features of which are disclosed in the patent to Ogden Minton, No. 1,280,065, dated September 24, 1918.

In computing machines which subtract, the handling of negative numbers is often a difficult proposition, both mechanically and functionally, since the digits ordinarily used for reading positive numbers do not display 15 the correct negative number when their wheels are rotated backwardly or operated in any way to effect subtraction, but instead display its complement less one. This "one" is known as a "fugitive" unit, and many 20 kinds of devices, for the most part extremely complex, have been devised for use in computing machines to care for this fugitive unit. Such devices usually involve some 25 modification of the carry-over mechanism, or of the adding-wheel-driving mechanism, or both, and not only add materially to the expense of building the mechanism, but also add seriously to its complexity and consequent liability to become deranged.

According to the present invention, practically all of these complexities may be avoided by employing a shutter, and an automatic control for the shutter, so that the shutter may be set to display the correct 30 digits.

The present invention is herein disclosed as an improvement on the co-pending application of Louis E. Giles, Serial No. 321,616, filed September 4, 1919, (now Patent No. 1,370,426, dated March 1, 1921,) wherein is shown an ordinary Underwood-Hanson or Underwood standard bookkeeping machine, having an additional set of dial numerals, especially arranged upon the dial wheels, 45 and a shutter which normally displays one set of digits, but which is adapted to be positioned by the typist to display other numerals, which, in the case of negative numbers, may be the numerals forming the 50 true answer. According to the form of the

present invention illustrated herein, the shutter, shown in said application, may be shifted, as shown and described therein, and there may be provided devices for automatically arresting the shutter when it arrives at the proper position. The mechanism may also include means for holding the shutter thus positioned until the typist has copied off the number displayed thereby, and means for automatically releasing it. One convenient form for effecting such result is in connection with the actuation of the general operator, which automatically takes place upon writing the units digit of the form of the Underwood-Hanson machine, shown in 60 said patent to Minton. For automatically arresting the shutter, it has been found advantageous to utilize the ordinary detents, which control the star-printing key; these detents being somewhat modified for the 65 purpose.

Other features and advantages will hereinafter appear.

In the accompanying drawings,

Figure 1 is a fragmentary plan view of an 80 Underwood standard bookkeeping machine of the kind referred to, many details being omitted.

Figure 2 is a sectional side view, showing 85 many of the parts shown in Figure 1, and also showing part of the driving mechanism for the numeral wheels.

Figure 3 is a plan view of part of Figure 1, but showing the shutter set to disclose the negative number "9,898,000." 90

Figure 4 is a fragmentary side view of a numeral wheel at "0," together with its detent and a few co-operating parts.

In an Underwood-Hanson combined typewriting and computing machine, numeral 95 keys (not shown) actuate the types (not shown), to print upon the platen (not shown).

Each numeral key, when actuated in a 100 computing zone, carries down its pin-setting bar 10 to set a corresponding pin 11 upon a pin-bar 12, which, at the moment, is shifted from its Figure 2 position to the usual computing position, the structure being more fully set forth in said Minton patent, and 105 in various other patents. When a number has been completely written by the numeral keys and set up by depressing the appropriate pins 11, it is carried into the numeral wheels 13 by actuating a general operator 110

14, which is drawn forward, as shown diagrammatically herein, by drawing forward a handle 15, so that a cross-bar 16, forming part of the operator, engages the 5 pin-bars 12 by their depressed pins and turns the numeral wheels 13 corresponding extents by means of racks 17 on the front ends of said pin-bars, said racks meshing with pinions 18, having a one-way connection with the numeral wheels 13. Usually in 10 these machines, the general operator 14 is actuated by an electrical motor, which is automatically started at the end of each computing zone. The motor, however, is not 15 shown in the drawings to avoid complexity. On the return stroke of the general operator 14, a carry-over drive-shaft 19 is rotated to drive any numeral wheels 13 whose carry-over wheels 20 may have been set upon the 20 forward movements of the general operator. The drive-shaft 19 is driven in the usual manner by the usual one-way clutch and pinion 21, which meshes with a rack-bar 22, forming part of the general operator. 25 To effect subtraction, a subtraction-key 23, of any ordinary or desired form, may be actuated before writing the digits of the number, and this subtraction-key in the Underwood-Hanson machine sets mechanism 30 for effecting complementary subtraction. This mechanism includes a "9" pin-setting bar 24 to set the "9" pins, and alters the connections from the numeral keys to the pin-setting bars 10, and also establishes a 35 connection from the numeral keys to a "9" pin-restoring bar 25.

In finishing computing operations on these machines in positive numbers, it is usual to subtract out the total shown upon the 40 numeral wheels 13 by printing the total as the final entry of the computation, and then to prove the correctness of the work by actuating a star-printing key 26, which is normally inoperable but which becomes operable when all the numeral wheels 13 stand at 45 "0." The connections for doing this are shown in some detail in the patent to Richard F. Hoyt, No. 1,256,309, dated February 12, 1918. As herein illustrated, the star-printing key 26 comprises a lug 27 which normally overlies a bail 28, journaled by arms 29 upon a shaft or on pivots 30. The bail 28 is pressed inwardly toward the wheels 13 by a spring 31, but is normally held in the 50 Figure 2 position under the lug 27, because one or more of the detents 32 (of which there is one for each numeral wheel 13) are pressed outwardly by the teeth 33 on their respective wheels 13. When any wheel stands at "0," 55 its detent 32 can seat itself in hollows 34, cut on the facing surfaces of the teeth 33, which are then adjacent the detent 32. When all the hollows 34 are in the position shown in Figure 4 for the nearest wheel 13, the 60 spring 31 carries the bail 28 toward the 65

wheels 13, clear of the lug 27. This, therefore, then enables the free actuation of the star-printing key 26.

Whenever the numbers subtracted upon the wheels 13 exceed the numbers added, 70 the positive digit "9" upon the left-hand numeral wheel 13 appears at the usual sight-opening along the lower edge of an opening 35 of the shutter 36. For reasons well known to those skilled in the art, this "9" is an indication that the numerals are to be reckoned as displaying a negative number, and not the true negative number itself, but its complement, save for the error of the fugitive unit. To enable the typist to read directly 75 from the numeral wheels 13 the true negative number represented by the complement shown, the shutter 36 is adapted to be shifted to the right by a handle 37, the shutter sliding on a suitable way 38, with the result that 80 the positive digits previously at the lower edge of the opening 35, so far as they are significant, are concealed by a stretch 85 of the shutter to the left of the handle 37.

To enable the true number to be read, the 90 numeral wheels 13, in addition to the digits shown adjacent the lower edge of the opening 35 in Figure 1, comprise negative read-in digits (usually red) shown in broken lines at an opening 39, in Figure 3. Said digits 95 are adapted to be read in part through said opening, and give the true reading and, therefore, are called negative digits. The positive and negative digits are arranged relatively to each other in the manner shown 100 and described in said above-mentioned application, Serial No. 321,616, with the result that each positive digit, when added to the adjacent negative digit on one side, will total nine, and, when added to the adjacent 105 negative digit on the other side, will total ten.

The shutter 36 is normally drawn to the extreme left by a spring 40 to the Figure 1 position, in which it is held arrested by its handle 37, which, in this position, lies against an edge 41 of the casing 42 of the machine. To read the correct negative number, the shutter is pulled to the right by its handle 37 until its handle conceals the extreme 110 right-hand positive significant numeral, at which position, according to the present invention, the shutter is automatically arrested, as will presently appear. In this position, which is the Figure 3 position, the wheel 13, 115 displaying the broken negative digit or numeral "8" at the handle 37, has the corresponding positive digit or numeral "2" concealed at the handle 37. The negative number to be read is partly through the opening 120 39, the upper edge of which is substantially in alignment with the lower edge of the opening 35, and partly at the upper edge 43 of the opening 35 beginning at a notch 48, and reads 009,898,000. When the shutter is 125 130

set at any position, such as the Figure 3 position, it is detained there by a pawl 44, which is normally drawn by a spring 45 to engage a rack 46, having teeth spaced to hold the shutter with its handle 37 intermediate any of the numeral wheels 13. This leaves both hands of the typist free to write, by the usual numeral keys, the negative numerals shown. An auxiliary shutter, which 10 may be used to normally conceal the negative numerals along the edge 43, and which may be automatically shifted to ineffective position at any movement of the handle 37 to the right, is omitted for simplicity in 15 the showing.

The shutter 36 may sometimes be drawn far enough to the right to carry the handle 37 into a notch 47 in the casing 42, in which position all of the positive numerals are 20 concealed. In this position of the shutter 36, all the negative numerals, except the extreme right-hand one, are read through the opening 39, the right-hand one being read at the edge 43. In other positions of the shutter 36, a less number of wheels 13 show their 25 negative numerals through the opening 39, so the negative numerals are to be read through the opening 39 as far as possible beginning at the left, and the remainder 30 along the edge 43.

To release the shutter when the typist has copied the numbers, the carry-over drive shaft 19 may be utilized, since it always actuates when computing the written digits. 35 There is provided on said shaft a cam 49 in which is a hollow 50 adapted to normally accommodate a toe 51 on an extension 52 of a pawl-releasing arm 53, which is journaled on a shaft 54 which carries the carry-over 40 wheels. The arm 53 extends into a somewhat enlarged opening 55 in the pawl 44, with the result that whenever the carry-over drive-shaft is actuated, the toe 51 rides out of the hollow 50 onto a long dwell 56 of the 45 cam 49, thus withdrawing the pawl 44 and holding it withdrawn until the drive-shaft 19 has substantially completed its operation. This finally brings the hollow 50 to the toe 51, allowing the spring 45 to make the pawl 50 again effective.

To automatically arrest the shutter 36 at the correct position when it is drawn to the right by the handle 37, the shutter is provided with a lug 57, which lies clear of the 55 usual positions of arresting lugs 58, forming the upper extensions of the detents 32. Whenever any detent 32 stands in the Figure 4 position, its arresting lug 58 stands in the path of the shutter lug 57, and prevents the 60 shutter from traveling farther. Thus, any feeler or detent 32, co-operating with its wheel at the "0" position, serves to arrest the shutter. To prevent the arresting of the shutter by a detent 32 in its "0" position, if 65 there is a numeral wheel to the right thereof

showing a significant digit, each detent 32 is shown herein as having a lug 59, which overlies the adjacent lug or detent to the right, with the result that if any detent 32 is held outwardly because its numeral wheel 70 stands in a non-zero position, its detent 32 will hold outwardly all of the detents 32 to its left, even though some of their wheels may stand at "0". This insures that the shutter, on being pulled to the right, is arrested with its handle 37 covering the right-hand significant positive numeral.

It will be observed that the bail 28 or an equivalent part may be entirely independent of the star-key 26. It is, however, shown 80 herein in such relation thereto to illustrate how the mechanism may be inserted in an ordinary standard machine.

In order to hold any detent or feeler 32 in its Figure 4 position when its wheel reaches its Figure 4 position, it is provided with a suitable individual spring 60. To hold the detents 32 against endwise displacement when the shutter strikes them, there is provided a comb 61, suitably supported in 85 the frame 42. To support the rear end of the shutter 36, there may be provided headed screws or rivets 62, which run in a slot 63 in the shutter. In Figure 3, the right-hand feeler or detent 32 is shown as provided with 90 the lug 59, which, however, is shown in said figure merely for the sake of clearness, and need not in practice appear.

Variations may be resorted to within the scope of the invention, and portions of the 100 improvements may be used without others.

Having thus described my invention, I claim:

1. In a computing machine, the combination with dial wheels having numerals for 105 positive numbers and numerals for negative numbers, of a shiftable shutter adapted to normally conceal negative numerals, and mechanical means for variably arresting the shutter to display the correct numerals when 110 shifted to display the negative numerals.

2. In a computing machine, the combination with dial wheels having numerals for positive numbers and numerals for negative numbers, of a manually shiftable shutter 115 adapted to be variously positioned to conceal some numerals and display others, and mechanical means for variably arresting the shutter at a point where it will display only correct negative numerals when negative 120 numbers are to be read.

3. In a computing machine, the combination with dial wheels having numerals for positive numbers and numerals for negative numbers, of a shutter, a feeler for each denomination adapted to be selectively positioned by the adjacent wheel, and a shutter-arresting lug co-operating with an effective feeler to arrest the shutter.

4. In a computing machine, the combina- 130

- tion with an array of dial wheels each having two sets of numerals thereon, one for positive numbers and one for negative numbers, of a detent for each wheel, a shutter 5 shiftable to selectively cover and uncover said numerals, and means whereby any detent may be positioned by its wheel to arrest the shutter.
5. In a computing machine, the combination with a casing having an opening and an array of numeral wheels readable through the opening, of a shutter slidable across said opening and normally concealing certain of the numerals, but comprising an opening 10 adapted to make them visible and conceal other numerals, a detent for each wheel adapted to be selectively positioned to arrest the shutter or let it pass, and means for detaining the shutter wherever it is positioned.
6. In a computing machine, the combination with a casing having an opening and an array of numeral wheels readable through the opening, of computing mechanism for 15 driving said wheels, a shutter slidable across said opening and normally concealing certain of the numerals, but comprising an opening adapted to make them visible and conceal the other numerals, means controlled by 20 the wheels for selectively arresting the shutter to selectively cover and uncover numerals, means for holding the shutter wherever it is positioned, and means automatically effective at the conclusion of an operation of the 25 computing mechanism for releasing the shutter to return it to normal position.
7. In a computing machine, the combination with a casing having an opening and an array of numeral wheels readable through 30 the opening, of computing mechanism for driving said wheels, a shutter slidable across said opening and normally concealing certain of the numerals, but comprising an opening adapted to make them visible and conceal the other numerals, a key adapted to 35 be used for clearance printing, detents controlled by the wheels for controlling said key, and means whereby said detents control the shutter for selectively arresting it to 40 selectively cover and uncover numerals.
8. In a combined typewriting and computing machine, the combination with a key adapted to effect clearance printing, of detents, numeral wheels adapted to variously 45 position said detents, means whereby in one position the detents block said key, and a shutter also controlled by said detents.
9. In a combined typewriting and computing machine, the combination with a key 50 adapted to effect clearance printing, of detents, numeral wheels adapted to variously position said detents, means whereby in one position the detents block said key, and a shutter also controlled by said detents, said 55 wheels comprising positive and negative 60 digits, adapted to be selectively and variably covered and uncovered by said shutter.
10. In a computing machine, the combination with numeral wheels, of a shutter adapted to be slid to selectively cover and uncover 65 numerals on said wheels, a feeler bearing radially upon each wheel, means whereby any feeler may become effective to arrest the shutter, and means whereby any feeler may be effective on any feeler to one side of it 70 while ineffective on the other feelers.
11. In a computing machine, the combination with numeral wheels, of a shutter adapted to be slid to selectively cover and uncover 75 numerals on said wheels, a pivoted feeler bearing radially upon each wheel, a lug on each feeler save one and overlapping the adjacent feeler on one side, so that one end feeler controls all the feelers to the other end, and means whereby any feeler may be 80 effective to arrest the shutter and make an adjacent feeler effective by its lug.
12. In a computing machine, the combination with numeral wheels, of a shutter adapted to be slid to selectively cover and uncover 85 numerals on said wheels, teeth on said wheels, detents adapted to seat themselves between said teeth, certain of said teeth being cut out to enable a detent to seat itself more deeply therein, means whereby any 90 detent holds out any detent to its left, and means whereby any detent arrests the shutter when slid from the left.
13. In a computing machine, the combination with numeral wheels, of a shutter 95 adapted to be slid to selectively cover and uncover numerals on said wheels, a pivoted feeler bearing radially on each wheel, a lug on each feeler save one and overlapping the adjacent feeler on one side, so that one 100 end feeler controls all the feelers to the other end, means whereby any feeler may become effective to arrest the shutter and make an adjacent feeler effective by its lug, means for 105 detaining the shutter when so slid, computing mechanism for driving the wheels, and connections for automatically releasing the shutter and returning it to normal position 110 at the end of an operation of the mechanism.
14. In a computing machine, the combination with a casing, of computing wheels having numerals visible through an opening of said casing, said numerals comprising positive numerals and negative numerals so arranged that a positive numeral foots to 115 ten with one adjacent numeral and to nine with the other adjacent numeral, a shutter normally exposing the positive numerals, means for shifting the shutter to expose some of the negative numerals, and means 120 associated with each numeral wheel adapted to be variably positioned thereby to be effective to arrest the shutter according to the position of its numeral wheel.
15. In a computing machine, the combi- 125

- nation with a casing, of computing wheels having numerals visible through an opening of said casing, said numerals comprising positive numerals and negative numerals so arranged that a positive numeral foots to ten with one adjacent numeral and to nine with the other adjacent numeral, a shutter normally exposing the positive numerals, means for shifting the shutter to expose some of the negative numerals, means associated with each numeral wheel adapted to be variably positioned thereby to be effective to arrest the shutter according to the position of its numeral wheel, computing mechanism for driving said wheels, and means controlled by the actuation of said mechanism to return said shutter from its shifted position to a normal positive reading position.
- 10 16. In a computing machine, the combination with a casing, of computing wheels having numerals visible through an opening of said casing, said numerals comprising positive numerals and negative numerals so arranged that a positive numeral foots to ten with one adjacent numeral and to nine with the other adjacent numeral, a shutter normally exposing the positive numerals, means for shifting the shutter to expose some of the negative numerals, means associated with each numeral wheel adapted to be variably positioned thereby to be effective to arrest the shutter according to the position of its numeral wheel, computing mechanism comprising devices on which numerals are temporarily set up, means for carrying the set-up numerals into the wheels, means for detaining the shutter in its shifted position, a carry-over drive-shaft adapted to carry-over on said wheels, and means controlled by said drive-shaft for returning the shutter to normal position.
- 15 17. In a computing machine, the combination with a casing, of computing wheels having numerals visible through an opening of said casing, said numerals comprising positive numerals and negative numerals so arranged that a positive numeral foots to ten with one adjacent numeral and to nine with the other adjacent numeral, a shutter normally exposing the positive numerals, means for shifting the shutter to expose some of the negative numerals, means associated with each numeral wheel adapted to be variably positioned thereby to be effective to arrest the shutter according to the position of its numeral wheel, a device for detaining the shutter in its shifted position, a spring normally tending to return it, computing mechanism for driving said wheels, and means actuated by said mechanism for automatically making the detaining device effective.
- 20 18. In a computing machine, the combination with a casing, of computing wheels having numerals visible through an opening of said casing, said numerals comprising positive numerals and negative numerals so arranged that a positive numeral foots to ten with one adjacent numeral and to nine with the other adjacent numeral, a shutter normally exposing the positive numerals, means for shifting the shutter to expose some of the negative numerals, means associated with each numeral wheel adapted to be variably positioned thereby to be effective to arrest the shutter according to the position of its numeral wheel, computing mechanism comprising devices on which numerals are temporarily set up, means for carrying the set-up numerals into the wheels, means for detaining the shutter in its shifted position, a carry-over drive-shaft adapted to carry-over on said wheels, and means controlled by said drive-shaft for returning the shutter to normal position.
- 25 19. In a computing machine, the combination with numeral-wheels having positive and negative digits thereon, of a feeler bearing upon each wheel, each of said wheels being so formed that the corresponding feeler will be in one position for a zero setting of said wheel and in another position for any other setting of the wheel, means whereby any one of said feelers when moved out of the position for a zero setting of the corresponding numeral-wheel will hold the feelers at the left thereof in corresponding positions, and means for reading negative results controllable by said feelers.
- 30 20. In a computing machine, the combination with dial-wheels having digits for positive numbers and digits for negative numbers, of a shiftable shutter adapted, when in normal position, to direct attention to positive digits, and means controllable by said wheels for variably arresting the shutter to direct attention to the correct negative digits when shifted to positions to read negative results.
